UNITED STATES PATENT OFFICE.

WILLIAM MILTON DAY, OF SMITHS FALLS, CANADA.

SNOWPLOW.

Application filed February 24, 1921. Serial No. 447,525.

To all whom it may concern:

Be it known that I, WILLIAM M. DAY, a citizen of the Dominion of Canada, residing at Smiths Falls, in the county of Lanark 5 and Province of Ontario, Canada, have invented certain new and useful Improvements in Snowplows, of which the following is a specification.

This invention relates to improvements in 10 snow plows to be used and driven by automobiles and other motor vehicles. The objects which I desire to attain are to construct a detachable snow plow which can be readily set up in position in front of a motor 15 vehicle and connected thereto and driven therefrom and actuated during the forward motion of the vehicle, so that the snow will be removed from the road and pulverized and delivered to a fan operating in 20 junction with the pulverizers, the fan being adapted to deliver the snow to the sides of the road.

It is also the object of this invention to 25 drive the fan and pulverizer from the driving axle of the motor vehicle, and to permit of the snow plow being removed from the motor vehicle when the snow plow is not required, so that the motor vehicle will thus 30 be capable of use for other purposes for which it was ordinarily designed.

I further desire to provide the plow with 35 a share which will be hinged so as to adjust itself to any unevenness of the road surface, and will be angularly inclined so that an even cleaning of the road of snow will 40 be attained, and to permit of this share being folded up in front of the plow when not in use.

Many other objects will be seen when the 45 invention is described in detail, and so that my invention will be understood I have illustrated a preferred embodiment of the same which will now be described, after which the novel features will be pointed out in the appended claims.

In the drawings, Figure 1 is a side elevation of an automobile with the improved plow attached to the front thereof.

Figure 2 is a front elevation of the plow

showing the radiator of the automobile behind.

Figure 3 is a perspective view of the snow plow detached from the automobile.

Figure 4 is a longitudinal section through the plow and fan casing. 55

Figure 5 is a transverse section through the fan casing.

Figure 6 is a front elevation of a part of 60 a plow showing the share folded up in closed position.

Similar symbols of reference indicate corresponding parts in the several figures.

Referring to the drawings, 1 indicates an automobile, on the front of which the snow plow 2 is mounted. 65

This snow plow consists of a casing 3 from which the bars 4 extend rearwardly, and these bars are bolted or otherwise secured to the chassis of the automobile, which will be elevated at the front to permit of this 70 connection with the bars being made, after which the automobile will be lowered.

The casing 3 is arcuate in cross section and is open at the front, being formed with a curved back wall 5 and side walls 6 which 75 converge towards the rear end.

A share 7 is hinged to the lower edge of the curved back wall 5, and is formed with side wings 8 which embrace the side walls 6. 80

On the bottom of the share 7 runners 9 are mounted, so that the share will run evenly over the snow and will adjust itself to any unevenness of the road.

Intermediate of the breadth of the casing 3 a fan casing 10 is mounted, and formed 85 with orifices 11 in the side walls, so that communication between the fan casing and the lateral compartments of the casing 3, formed by the said fan casing is obtained.

A shaft 12 extends through the casing 3 and fan casing 10 and is journaled in the side walls 6, and provided intermediate of its length with a disc 13 having peripheral vanes 14, the disc and vanes constituting a fan. 90

On the shaft 12 pulverizers 15 are mounted and located between the fan and the side walls 6 of the casing 3, and on one end of

the shaft a belt pulley 16 is keyed. This pulley 16 is enclosed in a casing 17 attached to the casing 3 and formed with orifices 18 in its upper wall, through which orifices the 5 belt 19 passes.

The belt 19 engages with a pulley 20 mounted on the intermediate shaft 21, which is journalled in suitable bearings at the front. A driven pulley 22 is keyed to the 10 shaft 21 and is connected by a belt 23 to the drive pulley 24 on the rear driving axle of the automobile.

The pulley 20 will be controlled by suitable clutch mechanism on the shaft 21.

15 It will be evident by reference to Figure 2 that by having the side walls 6 converging, proper clearance will be obtained for the belt drive 19 and also for the front wheels of the automobile.

20 The fan casing 10 is provided with a suitable discharge conduit 25 having a folding adjustable hood 26 on the discharge end thereof, and at the front lower end of the fan casing a dividing and spreading device 25

27 is formed. This spreading and dividing device is a wedge shape, having lateral walls which diverge towards the rear, leaving a forward cutting edge which will divide the snow and deliver it to the lateral compartments of the casing 3.

The share 7 when in a lowered position engages with a stop member 28 projecting forwardly and below the casing 3, and the share is thus prevented from digging too 35 deeply into the snow and blocking.

When the snow plow is not in use the share 7 is rotated around its hinges to close the lower portion of the front of the casing 3 and the share is retained in this position by 40 clips 29.

When the snow plow is in use the motor vehicle is driven forward, and during this motion the snow plow is fed against the snow, and the fan and pulverizing members 45 are operated. As the share 7 engages the snow, the snow is delivered to the casing 3 and engaging with the divider and spreader 27, the snow is delivered to the compartments of the casing 3 on each side of the fan.

50 The pulverizers 15 break up the snow and as the blades of the pulverizers are offset they throw the snow towards the fan which is being rotated at a high speed.

The vanes 14 of the fan engage the snow 55 and deliver it to the discharge 25 of the fan, and the snow passing through the adjustable hood 26 is delivered to the side of the road, the main portion of the road is thus easily cleared of snow and available for traffic.

60 The belt pulley 16 on the shaft 12 is thoroughly protected against snow and ice which cannot interfere with the operation of the plow.

What I claim as my invention is:

65 1. The combination with a motor vehicle,

of a snow plow located in front thereof and comprising a casing open at the front and having lateral compartments, bars extending rearwardly of the casing for attachment to the motor vehicle, a share hinged to the 70 casing, a fan casing in said casing and disposed between said lateral compartments, a fan operating in the fan casing, a fan shaft extended transversely of the direction of movement of the plow, a dividing and 75 spreading device at the front lower end of the casing, pulverizing elements operating in said compartments at the sides of the fan, and means for operating the fan and the pulverizing elements. 80

2. The combination with a motor vehicle, of a snow plow located in front thereof and comprising a casing open at the front and having lateral compartments, bars extending rearwardly of the casing for attachment to 85 the motor vehicle, a share hinged to the casing, a fan casing in said casing and disposed between said lateral compartments, a fan operating in the fan casing, a fan shaft extended transversely of the direction of movement of the plow, a dividing and spreading device at the front lower end of the casing, pulverizing elements operating in said compartments at the sides of the fan, and means for operating the fan and the 90 pulverizing elements, said device being wedge shape and having a forward cutting edge. 95

3. The combination with a motor vehicle, of a snow plow located in front thereof and comprising a casing open at the front and having lateral compartments, bars extending rearwardly of the casing for attachment to the motor vehicle, a share hinged to the casing, a fan casing in said casing and disposed 100 between said lateral compartments, a fan operating in the fan casing, a fan shaft extended transversely of the direction of movement of the plow, a dividing and spreading device at the front lower end of the casing, 105 pulverizing elements operating in said compartments at the sides of the fan, means for operating the fan and the pulverizing elements, and a stop member projecting from the first-named casing to engage the share. 110

4. A snow plow to be used with motor vehicles, comprising a casing open at the front and having lateral compartments, a fan casing between said lateral compartments, a fan shaft extended transversely of the direction 120 of movement of the plow, a fan on said shaft, a wedge shaped dividing and spreading device at the front lower end of the fan casing, pulverizing elements on the fan shaft, a pivoted share, and means for rotating said fan shaft. 125

5. A snow plow to be used with motor vehicles, comprising a casing open at the front and having lateral compartments, a fan casing between said lateral compartments, a fan 130

shaft extended transversely of the direction of movement of the plow, a fan on said shaft, a wedge shaped dividing and spreading device at the front lower end of the fan 5 casing, pulverizing elements on the fan shaft, a pivoted share, and means for rotating said fan shaft from the driving axle of the motor vehicle, the snow being delivered to the plow by the forward movement of the motor vehicle, and means to deliver 10 the snow to the side of the road.

In testimony whereof I affix my signature in the presence of two witnesses.

WILLIAM MILTON DAY.
